DRIVING AND POSITIONING MECHANISM FOR DRUM TYPE CONTROLLER

Clyde F. Robbins, Milwaukee, Wis., assignor to Cutler Hammer Inc., Milwaukee, Wis., a corporation of Delaware

Application July 2, 1957, Serial No. 669,624

14 Claims. (Cl. 74—143)

This invention relates generally to drum type controllers for electrical devices.

More particularly the invention relates to mechanisms for driving and positioning the rotatable drum cylinder of heavy duty controllers.

When rotating the drum cylinder of controllers, particularly those designed to handle extremely large values of current, overtravel of the cylinder or failure to stop exactly at a desired position may accidentally establish and/or interrupt electrical contact between certain of the movable and stationary contact members employed in the controller.

Thus, arcing may occur causing welding, pitting, burning and other types of damage to the contact members and other portions of the controller. Some mechanisms dependent on the skill of the operator to attain accurate drum cylinder positioning have proven unsatisfactory. Therefore, it is desirable to provide improved means for driving and positioning drum cylinders.

It is an object of this invention to provide improved means for rotating the drum cylinder of electrical controllers whereby accurate drum cylinder positioning is obtained and overtravel is prevented.

Another object is to provide such means which positively rotate the drum cylinder a predetermined distance during each operation.

Still another object is to provide such means whereby the drum cylinder may be rotated step-by-step in either forward or reverse direction.

A further object is to provide improved manual operating means for drum controllers which require no special skill to operate correctly.

Other objects and advantages of the invention will hereinafter appear.

The accompanying drawings illustrate one embodiment of the invention which will now be described, it being understood that the embodiment illustrated is susceptible of modification with respect to certain structural details thereof without departing from the scope of the appended claims.

In the drawings:

Figure 1 is a top plan view of the driving and positioning mechanism associated with a drum type controller;

Fig. 2 is a rear elevational view of the mechanism shown in Fig. 1;

Fig. 3 is a cross sectional view of the mechanism taken along line 3—3 of Fig. 1;

Fig. 4 is an enlarged cross sectional view of an element of the mechanism; and

Fig. 5 is a front elevational view showing a portion of the mechanism.

In the drawings, the numeral 11 designates a heavy duty drum type electrical controller comprising a frame and a rotatable drum cylinder (not shown), the shaft 12 of which is supported at its lower end by bearing means (not shown). The upper portion of shaft 12 extends through an opening in a bearing plate 13 which is bolted

2

to the top surface of the frame of the controller and the upper end of the shaft is supported by bearing means 14 carried by a bearing support member 15. Bearing support 15 is bolted to bearing plate 13.

5 Referring to Fig. 3, the hub 16 of a star wheel 17 is rigidly affixed to shaft 12 so that rotation of the star wheel effects rotation of the drum cylinder. The star wheel shown has nineteen notches, each spaced an angular distance of seventeen degrees from an adjacent notch, and 10 the sides of each notch meet to form a right angle. A portion of the star wheel is unnotched, as Fig. 1 shows.

A bevel gear 18 secured to shaft 12 meshes with another bevel gear 19 which is secured to a shaft 20 supported by bearing support 15. Gears 18 and 19 and a 15 portion of shaft 20 have been deleted from Fig. 1 to simplify the drawing. Shaft 20 is mechanically connected to another shaft 21 which extends through an opening in a control panel 22. The panel is attached to, or may merely have a fixed position with respect to, the frame of 20 the controller 11. A hand wheel 23, the purpose of which will hereinafter be explained, is secured to the end of shaft 21 projecting from the face of the panel. The hub of the hand wheel 23 has a pointer 23a integral therewith which indicates by its position with respect to 25 indicia provided on the face of panel 22 the contact position of the drum cylinder, as Fig. 5 makes clear.

Two independently movable levers or operating members 24 and 25, each of which has a circular hole through its inwardly disposed end, are rotatable on hub 16. As 30 Fig. 3 shows, suitable spacer washers 26 and 27 are disposed on the hub between the star wheel and lever 24 and between both levers, respectively. A resilient retaining ring 28 which is securely in a groove formed about the upper end of hub 16 serves to hold the levers and 35 washers on the hub.

As Figs. 1 and 2 make clear, the outer ends of the levers 24 and 25 are pivotally connected to the angle brackets 29 and 30, respectively, by the pins 31 and 32, respectively, and the brackets, in turn, are rigidly secured 40 to the threaded ends of the push rods or tie rods 33 and 34, respectively, by pairs of adjustable securing nuts. For convenience in illustration, Figs. 1 and 3 show the rods 33 and 34 (which are movable to pivot the levers) as broken, but it is to be understood that the rods are 45 single, continuous lengths of material substantially equal to each other in length. The rods 33 and 34 extend through the bushings 35 and 36, respectively, which are secured to panel 22 by the nuts 37 and 38, respectively, and suitable mushroom head pushbuttons 39 and 40 are attached to the ends of the rods projecting from the face of the panel. Since the path of travel of the outer ends of the levers 24 and 25 is arcuate, the path of travel of each rod will not be coincidental with the longitudinal axis of the rod. Therefore, to prevent binding or "window-locking" of the rods in their respective bushings, each bushing is designed, as Fig. 4 shows, so that the rod bears on the relatively small surface 41 rather than on 50 surface 42.

Rod travel (and thus lever travel) is limited by stoppers, 60 preferably formed of rubber or other suitable resilient material, which are force-fitted on the rods. Stoppers 43 and 44 limit outward travel, and similar stoppers 45 and 46 limit inward travel. Movement or displacement 65 of the stoppers on the rods due to repeated bumping against the bushings is prevented in the case of stoppers 45 and 46 by the shanks of the pushbuttons 39 and 40, respectively, and is prevented in the case of stoppers 43 and 44 by the hollow tubular members 47 and 48, respectively, which are disposed on the rods 33 and 34, respectively, between the stoppers 43 and 44 and the nut assemblies 49 and 50, respectively.

Figs. 1, 2 and 3 show a relatively large, substantially flat mounting plate 51 bolted to the upper surface of bearing plate 13. Fig. 2 best shows how the opposite extremities of the mounting plate are upwardly bent, one slightly more than the other, to afford support for levers 24 and 25 which ride thereupon, while Fig. 3 best shows how the rearward extremity of the mounting plate is upwardly bent and provided with tapped openings to receive the screws which secure the cover 52 to the mechanism. Two relatively long angle brackets 53 and 54 are rigidly secured to mounting plate 51 and serve to anchor corresponding ends of the tension springs 55 and 56, respectively, which are attached at their other ends to levers 24 and 25, respectively. Each spring (portions of which have been deleted from Fig. 1) tends to bias its associated lever toward normal position, that is, toward panel 22 as far as the stoppers 43 and 44 will allow. For purposes of illustration, Figs. 1 and 2 show lever 25 biased in normal position, while lever 24 is shown moved to its extreme operating position, that is, away from panel 22 as far as stopper 45 will allow. However, when rod 33 is not depressed spring 54 moves lever 24 to normal position.

Referring to Figs. 1 and 2, it is seen that pawl blocks 57 and 58 are pivotally attached to the underside of the levers 24 and 25, respectively, by the pins 59 and 60, respectively. Tension springs 61 and 62 are attached to the pawls 57 and 58, which have portions adapted to engage the star wheel notches. The tension springs 61 and 62 are anchored to the relatively small angle brackets 63 and 64, respectively, which are rigidly secured to levers 24 and 25, respectively. If preferred, the springs 61 and 62 may be anchored directly to mounting plate 51 instead of to the respective lever arms, provided, of course, that suitable provisions are made therefor.

As Fig. 1 makes clear, when the levers 24 and 25 are biased in normal position, the tension springs 61 and 62 would tend to bias the pawls 57 and 58, respectively, against the throwout pins 65 and 66, respectively. The pawls are thus kept clear of the star wheel. If preferred, the throwout pins 65 and 66 may be rigidly secured directly to mounting plate 51. However, as it may be necessary to adjust the positions of these pins to compensate for tolerances and to insure that the pawl blocks are properly disposed with respect to the star wheel, it is desirable that the throwout pins 65 and 66 be affixed to movable adjustment plates such as 67 and 68, respectively. The adjustment plates 67 and 68 are pivotally secured to mounting plate 51 by the rivets 69 and 70, respectively, but are normally held immobilized by the screws 71 and 72, respectively, which extend through slots provided in the adjustment plates and take into tapped holes provided therefore in mounting plate 51.

Mounting plate 51 is provided with two rigidly attached stop posts 73 and 74 which have rectangular cross sections and which serve to limit the travel of the pawl blocks 57 and 58 as will hereinafter be explained.

To prevent undesired rotation of the drum cylinder, one of the notches of star wheel 17 is engaged by a roller 75 carried by the star wheel roller lever 76 which is pivotable on a pin or post 77 rigidly secured to mounting plate 51. A tension spring 78, having one end secured to a portion of roller lever 76 and its other end anchored to a bracket 79 rigidly secured to mounting plate 51, tends to bias roller 75 firmly against the star wheel. Roller 75, while not preventing intentional movement of the drum cylinder, tends to hold it in the position to which it is moved.

Let it be assumed that the drum cylinder has a total of eleven definite operating positions with respect to the frame of the controller. It will be apparent that although star wheel 17 has a total of nineteen notches each pawl can engage eleven of such notches since star wheel rotation in either direction is limited by the unnotched portion of the star wheel. Star wheel 17 is shown disposed in a centered position which corresponds to the sixth op-

erating position of the drum cylinder. Assuming that both levers (and their associated parts) are biased in normal position, depression and release of pushbutton 39 would effect rotation of the drum cylinder one step (see Fig. 1) from position six to position five. Repeated actuation of pushbutton 39 would move it from position five to four. Obviously, actuation of pushbutton 40 would effect step-by-step movement of the drum cylinder in the direction opposite to the arrow (see Fig. 1). Each movement of the drum cylinder is accompanied by a corresponding change in position of pointer 23a on hand wheel 23. Hand wheel 23 may be employed to rotate the drum cylinder in a rapid, continuous movement to its starting position, or other desired position, should step-by-step movement no longer be necessary, as when the controller is deenergized for any reason.

Although each step of drum cylinder rotation is effected by full depression of a pushbutton in a rapid, continuous stroke followed by release of the pushbutton, operation of the mechanism will be best understood by a detailed analysis of the movement of the drum one step in the direction of the arrow (see Fig. 1). As pushbutton 39 is depressed, rod 33 begins to move inward to effect pivoting of lever 24 in the direction of the arrow (see Fig. 1). Lever 24 carries pawl block 57 with it, but simultaneously tension spring 61 tends to pull the pawl block against and around throwout pin 65 so that the corner 57a of the pawl block is directed toward the star wheel. Corner 57a, which is rectangularly shaped to match the star wheel notches, slips into notch 17a. As lever 24 advances further, pawl block 57 is moved away from throwout pin 65 and being engaged with a star wheel notch, effects rotation of the drum cylinder. Rotation continues 35 any preselected distance until lever travel is checked. Lever travel may be checked either by having the pawl block 57 slam into stop post 73 or by having stopper 45 hit bushing 35. Since the drum cylinder contemplated herein has considerable mass and momentum, the former 40 method of stopping is accompanied by considerable shock and noise. Therefore, the latter method is preferred. By adjusting the nut assembly which secures bracket 29 to rod 33, the stroke of lever 24 may be shortened so that resilient stopper 45 hits bushing 35 slightly before 45 face 57b of pawl block 57 meets stop post 73. The momentum of the drum cylinder, however, causes the star wheel to thrust the pawl block against the stop post thus 50 insuring that the drum cylinder has traveled its preselected distance but preventing the possibility of drum cylinder overtravel. When notch 17a has moved to the position 17b the drum cylinder has been moved an exact, predetermined distance in a swift, sure movement. Pushbutton 39 is released and tension spring 55 tends to pull lever 24 back toward its normal position. Pawl block 55 57, due to the tapered configuration of that portion locking the drum against further rotation, is readily withdrawn from between the star wheel and stop post no matter how firmly the star wheel may have been thrust against it. As lever 24 moves further back, spring 61 60 draws the pawl block against throwout pin 65 and clear of the star wheel. It is essential that the pawl block be moved clear of the star wheel so that the mechanism be in readiness for movement of the drum cylinder in the reverse direction, should such be desirable. It is to be 65 understood that lever 25 and the parts associated therewith operate in a manner similar to that described to effect step-by-step rotation of the drum cylinder in the opposite direction.

Rotation of star wheel 17 beyond position one or eleven is impossible by movement of the levers since the pawl blocks would be brought into engagement with the unnotched portion of the star wheel, while further rotation through use of hand wheel 23 is prevented by the lugs 80 and 81 (Figs. 2 and 3) rigidly affixed to the underside of

the star wheel 17 which would come into abutment with the base of bearing support 15.

The mechanism is susceptible of various modifications. Star wheels having other shapes or greater or lesser numbers of notches may be employed provided that suitable changes are made in parts associated therewith. Thus, a star wheel notched completely about its periphery, and not provided with lugs 80 and 81, may be employed to obtain continuous step-by-step movement in either direction. If preferred, other lever moving arrangements may be employed, such as moving them directly or by electro-magnetic means, or linkages requiring them to be pulled rather than pushed.

I claim:

1. In a step-by-step operating and positioning mechanism for a controller having a rotatable operating shaft, in combination, a star wheel to effect rotation of said shaft, an operating member normally biased to a given position and movable a predetermined distance against said bias, a pawl, means to afford engagement of said pawl with said star wheel and move the latter a given angular distance in one direction when said member is moved said predetermined distance against its bias, means acting upon said pawl when said operating member has moved said predetermined distance to stop rotation of said star wheel in said one direction, and means biasing said pawl out of engagement with said star wheel when said member returns to its given position.

2. As a step-by-step operating and positioning mechanism for a controller having a rotatable operating shaft, in combination, a star wheel to effect rotation of said shaft, at least one operating member, said member normally disposed in a given position and movable a predetermined distance therefrom, a pawl movable by said operating member to effect rotation of said star wheel in one direction, said pawl normally disengaged from said star wheel when said operating member is disposed in said given position, means to effect engagement of said pawl with said star wheel as said operating member moves away from said given position, and means acting upon said pawl when said operating member has moved said predetermined distance to stop rotation of said star wheel in said one direction.

3. As a step-by-step driving and positioning mechanism for a drum controller having a drum member rotatable in forward and reverse directions, in combination, a star wheel to effect rotation of said drum member, at least one operating member pivotable about said star wheel, said member normally disposed in a given position and pivotable a predetermined distance therefrom, a pawl carried by said operating member to effect rotation of said star wheel in one direction, means to maintain said pawl disengaged from said star wheel when said operating member is disposed in said given position, said means effecting engagement of said pawl with said star wheel as said operating member moves away from said given position, and means acting upon said pawl when said operating member has moved said predetermined distance to stop rotation of said star wheel.

4. The combination according to claim 3 wherein said first mentioned means comprise biasing means associated with said pawl and fixed means against which and about which said pawl is biased.

5. As a step-by-step driving and positioning mechanism for a drum controller having a drum member rotatable in forward and reverse directions in combination, a star wheel to effect rotation of said drum member, a base, at least one operating member pivotable about said star wheel, said member normally biased in a given position with respect to said base and pivotable a predetermined distance therefrom, a pawl carried by said operating member to effect rotation of said star wheel in one direction, biasing means associated with said pawl, means fixed with respect to said base against which said pawl is biased when said operating member is disposed in said given position

thereby maintaining said pawl disengaged from said star wheel, said means cooperating with said pawl to effect engagement of said pawl with said star wheel as said operating member moves away from said given position, and means fixed with respect to said base which engage said pawl when said operating member has moved said predetermined distance to prevent further rotation of said star wheel.

6. The combination according to claim 5 wherein said biasing means associated with said pawl is anchored to said operating member.

7. The combination according to claim 5 wherein said biasing means associated with said pawl is anchored to a point fixed with respect to said base.

8. The combination according to claim 5 wherein said pawl and said last mentioned means are shaped and disposed with respect to each other so that said pawl may be readily withdrawn from between said star wheel and said last mentioned means.

9. As a step-by-step driving and positioning mechanism for a drum controller having a drum member rotatable in forward and reverse directions, in combination, a star wheel to effect rotation of said drum member, two operating members, each member normally disposed in a given position and movable a predetermined distance therefrom, two pawls, one of said pawls movable by one of said operating members to effect forward rotation and the other movable by the other of said operating members to effect reverse rotation of said star wheel, each pawl normally disengaged from said star wheel when the operating member associated therewith is disposed in said given position, means to effect engagement of each pawl with said star wheel as the operating member associated therewith moves away from said given position, and means acting upon each pawl when the operating member associated therewith has moved said predetermined distance to stop rotation of said star wheel in the direction in which it is moving.

10. As a step-by-step driving and positioning mechanism for a drum controller having a drum member rotatable in forward and reverse directions, in combination, a star wheel to effect rotation of said drum member, two operating members pivotable about said star wheel, each member normally disposed in a given position and pivotable a predetermined distance therefrom, a pawl carried by each operating member, one pawl movable by one of said operating members to effect forward rotation of said star wheel and the other pawl movable by the other of said operating members to effect reverse rotation of said star wheel,

50 means associated with each pawl to maintain said pawl disengaged from said star wheel when the operating member carrying said pawl is disposed in said given position, said means effecting engagement of said pawl with said star wheel as the operating member carrying said pawl moves away from said given position, and means acting upon each pawl when the operating member carrying each pawl has moved said predetermined distance to stop rotation of said star wheel.

11. As a step-by-step driving and positioning mechanism for a drum controller having a drum member rotatable in forward and reverse directions, in combination, a star wheel to effect rotation of said drum member, a base, two operating members pivotable about said star wheel, each member normally biased in a given position

65 with respect to said base and pivotable a predetermined distance therefrom, a pawl carried by each operating member, one pawl movable by one of said operating members to effect forward rotation of said star wheel and the other pawl movable by the other of said operating members to effect reverse rotation of said star wheel, biasing means associated with each pawl, means fixed with respect to said base against which each pawl is biased when the operating member associated therewith is disposed in said given position thereby maintaining each pawl disengaged from said star wheel, said means

cooperating with each pawl to effect engagement of each pawl with said star wheel as the operating member associated therewith moves away from said given position, and means fixed with respect to said base which engage each pawl when the operating member associated therewith has moved said predetermined distance to prevent further rotation of said star wheel.

12. The combination according to claim 11 including means responsive to the movement of said drum member to indicate the position wherein said drum member is disposed.

13. The combination according to claim 11 including means to rotate said drum member in either direction when each pawl is disengaged from said star wheel.

14. As a step-by-step operating and positioning mechanism for a controller having a rotatable operating shaft, in combination, a star wheel to effect rotation of said shaft, two operating members pivotable about said star wheel, each member normally biased to a given position and pivotable therefrom, means rectilinearly movable to move each operating member a predetermined distance, a pawl carried by each operating member, one

5 pawl movable to effect forward rotation of said star wheel and the other pawl movable by the other of said operating members to effect reverse rotation of said star wheel, means associated with each pawl to maintain said pawl disengaged from said star wheel when the operating member carrying said pawl is biased to said given position, said means effecting engagement of said pawl with said star wheel when the operating member carrying said pawl is moved away from said given position, and means 10 acting upon each pawl when the operating member carrying each pawl has moved said predetermined distance to stop rotation of said star wheel.
